AERIAL SYSTEM FOR WIRELESS SIGNALING

Filed Nov. 15, 1928

Inventor
THOMAS L. ECKERSLEY

By his Attorney *Gray, Adams*

UNITED STATES PATENT OFFICE

THOMAS LYDWELL ECKERSLEY, OF DANBURY, ENGLAND, ASSIGNOR TO RADIO CORPORATION OF AMERICA, A CORPORATION OF DELAWARE

AERIAL SYSTEM FOR WIRELESS SIGNALING

Application filed November 15, 1928, Serial No. 319,707, and in Great Britain November 18, 1927.

This invention relates to aerial systems for wireless signaling, and has for its principal object to provide an aerial system which, while simple and cheap to construct, shall be capable of more efficient radiation or reception.

When a plurality, say, two, similar aerials are coupled to a single load and are sufficiently separated as substantially not to interfere with one another, each aerial will receive a definite amount of energy, one half of which is supplied to the load. If, therefore, the two aerials are properly coupled to the load, the energy which will be received from the two aerials is twice that which would be received upon a single aerial.

It has been generally assumed that there is a definite amount of energy which each aerial can draw from the ether and that each can only draw this amount when it is completely separated from the other, so that the maximum amount of energy which is commonly believed to be obtainable from two aerials is twice that obtainable from one.

I have found, however, that by correctly separating a pair of aerials and arranging them so that the E. M. F. therein is in phase, it is possible to cause each aerial to assist the other in drawing from the ether more energy than it could draw alone, and that a similar advantage can be obtained when the aerials are employed to transmit.

If two aerials receive a current I and the E. M. F. in each is E , then, if the E. M. F. is in phase with the current, the gross energy in the pair of aerials is $2EI$. Using the customary symbols of R for the radiation resistance of the two aerials (i. e. of the system) and R_L for the effective resistance of the load, the energy received by the load will be $(2 \times I)^2 R_L$ and the energy re-radiated $(2 \times I)^2 R$. Obviously, equilibrium is reached when $2EI = (R + R_L) (2 \times I)^2$, i. e. when

$$2I = \frac{E}{R + R_L},$$

and since maximum energy is supplied to the

load when $R_L = R$, for the condition of maximum supply to the load

$$2I = \frac{E}{2R} \text{ and } R_L(2 \times I)^2 = \frac{E^2}{4R}.$$

55

Hence, it follows that the maximum amount of energy will be supplied to the load when the radiation resistance of the system is reduced to a minimum. The radiation resistance of the system is a function of the separation of the aerials, and the value

$$\frac{R}{R_o}$$

(where R_o is the radiation resistance of a single aerial) has a fairly well marked minimum when the separation of the aerials is .57 of the wave length, at which separation

the ratio $\frac{R}{R_o} =$ (approximately) .3. Thus, if 70 a pair of aerials be separated by .57 of the wave length, the energy which is usefully receivable by the pair is about three times that usefully receivable by a single aerial, and 50% better than that usefully receivable by a pair of similar aerials widely separated, 75 for in this last case the ratio

$$\frac{R}{R_o}$$

80

will approximate to .5.

According to this invention an aerial system comprises a plurality of aerials coupled to a single circuit and adapted to be energized in phase, the separation of the said aerials being such that the actual radiation resistance of the system as a whole is less than the radiation resistance calculated from the radiation resistance of the separate aerials considered as in parallel.

Preferably the separation of adjacent aerials is approximately .57 of the wave length, and should not exceed .75 of the wave length or be less than .43 of the wave length.

Marked advantages are obtained when the separation lies between .5 and .68 of the wave length.

When the aerials are employed for transmission, the single circuit coupled thereto is,

90

85

95

100

of course, constituted by a transmitter, while when the aerials are employed for reception, the said circuit is constituted by a receiving circuit and the aerials are energized in phase by being erected in a line at right angles to the direction of the incoming signals.

In one way of carrying out the invention, a pair of vertical aerials, each containing a series tuning condenser is erected at a separation of .57 of the wave length and the energy from each of the said aerials is supplied via a tapped aerial transformer and a feeder to a pair of tappings upon an inductance coil forming part of a tuned circuit. The two tuned circuits are coupled to a single coil associated with an amplifier and receiver.

The invention is illustrated in the accompanying drawing, which shows schematically one arrangement in accordance therewith.

Referring to the drawing, A, B are two similar aerials of any known kind, for example, they may be ordinary open aerials or they may be vertical aerials whose length is a multiple of a half wave length, and in which the radiation from alternate half wave lengths is annulled or reduced. The aerials A, B are separated by a distance of from .43 to .75 of a wave length, but preferably by a distance equal to .57 of a wave length, and are connected at tapping points T₁, T and T₂, T, to a pair of parallel connected feeders P, Q which are in turn coupled through a 2 to 1 ratio transformer T₃ to a main feeder F, leading to a transmitter or receiver as the case may be. The tappings T₁, T T₂, T should be such that the impedance T₁, T equals the surge impedance of the aerial A, while the impedance T₂, T equals that of the aerial B.

It is found that with the arrangement above described maximum radiation or signal strength is obtained in or from a direction substantially at right angles to the line A, B, while it will be seen that the installation is very simple and cheap.

No claim is made in this specification to so-called "beam" aerial systems, comprising a plurality of aerials energized in phase and spaced apart by approximately not more than one half wave length, so as to constitute sheet aerials. The present invention may be regarded as providing an aerial system giving results comparable to those obtainable from beam aerials but of greater simplicity and less cost.

Having now particularly described and ascertained the nature of my said invention and in what manner the same is to be performed, I declare that what I claim is:

1. An aerial system comprising a plurality of aerials coupled to a single circuit and adapted to be energized in phase, the separation of said aerials being more than .5 and less than .68 of a wave length whereby the

actual radiation resistance of the system as a whole is less than the radiation resistance of the separate aerials considered in parallel.

2. An aerial system comprising a plurality of aerials coupled to a single circuit and adapted to be energized in phase, the separation of said aerials being .57 of a wave length whereby the actual radiation resistance of the system as a whole is less than the radiation resistance of the separate aerials considered in parallel.

3. An antenna system comprising a pair of vertical linear radiators separated horizontally substantially .57 of a wave length, a transformer in series with each of said radiators, parallel feeders connecting the transformers together, the feeders being tapped to points on the transformer such that the portion of the transformer included between the feeder tapping points equals, for each radiator, the surge impedance of the corresponding radiator, a transformer connected across said feeders, and, a transmission line tapped to said last mentioned transformer.
